UNITED STATES PATENT OFFICE.

RICHARD SAVAGE, OF SAN FRANCISCO, CALIFORNIA.

FIRE-PLACE.

SPECIFICATION forming part of Letters Patent No. 393,178, dated November 20, 1888.

Application filed May 28, 1887. Serial No. 239,708. (No model.)

To all whom it may concern:

Be it known that I, RICHARD SAVAGE, of the city and county of San Francisco, State of California, have invented an Improvement in 5 Fire-Places; and I hereby declare the following to be a full, clear, and exact description of the same.

My invention relates to certain improvements in fire-place grates and mechanism connected therewith. It consists in certain details 10 of construction, which will be more fully explained by reference to the accompanying drawings, in which—

Figure 1 is a front view of the grate. Fig. 15 2 is a side view. Fig. 3 is a vertical section.

The object of this grate is to increase the heating capacity and economical effects, and to make it more cleanly and easier to operate, while all the parts are easily accessible for 20 purposes of repair or otherwise.

A is the outer casing having the front B, the basket C, and the grate D. The back and sides of the basket are so made in sections, B', that they may be easily taken down or 25 removed for inspection without disturbing other parts of the structure.

At the rear of the fire-place is an open space, E, into which air is admitted through passages E' on the sides of the grate and is there 30 heated, and escaping upward is allowed to go out through the openings in the upper part of the front B and be discharged into the room.

In order to obtain the best effects of the heat 35 of the fire, I have formed the back of the fire-place with pins or lugs F, which are cast with the back, so that the outer ends project into the fire-place, as shown, while the inner ends extend back into the air-space behind the fire-place. The air is thus compelled to circulate 40 among these heated pins and is much more rapidly heated. In addition to this space is another transverse channel, G, connecting the two side spaces, E, which extend back each side of the fire-place to the rear of the chamber. Behind the air-space is a chamber, H, 45 in the upper part of which is the opening from the fire-place to the chimney a. This chamber H extends down behind the air-space, and by means of a passage, b, below the grate connects with the ash-pit. Within this chamber 50 are two dampers, I and J, which are oper-

ated by rods and knobs K K', extending out through the front at any convenient point. The damper I when closed prevents the passage of air beneath the grate and so on up into 55 the chimney. When open, as in case of shaking the fire down or dropping the ashes into the ash-pit c, a certain draft is produced through the ash-pit and up into the chimney-flue, which carries away all dust and prevents 60 its escaping into the room. The upper damper, J, opens or closes the direct passage to the chimney by connecting levers to the knob K'. When open, it produces a direct draft from the 65 grate to the chimney, which is necessary to get the fire fairly started, and after the fire is well started it may be closed, thus directing the smoke and heat down the rear flue, thereby saving a large amount of heat from waste.

The grate is journaled by means of pins at 70 either end. One of these pins or journals is made with a square end to enter a similarly-shaped hole upon the end of the lever L for the purpose of shaking and dumping. From this lever a rod, M, extends out through the 75 side of the front frame, having a knob or handle, d, by which it may be operated to shake or dump the grate when desired. The whole space around the fire-place casing, both at sides, back, and top, receives air which is 80 heated by contact with the casing-plates and the projecting pins at the back and flanges upon the sides, as shown, as well as by passing through the transverse opening G, before described. This heated air is all discharged 85 into the room from the upper part of the front frame, B, which is perforated on the top and sides; or it may be conducted by a register into another room at the rear of the fire-place, or by a flue or pipes into an upper room or 90 rooms, thus adding considerably to the effect of the grate.

The front bars of the basket are made right-angled-triangular in section, the right-angular sides forming the front and bottom of each 95 bar, while the hypotenuse inclines downward and inward from the upper acute angle. This prevents dust from lodging upon the top of the bars and causes it to slide down into the fire, instead of falling out into the room.

The ash-pan f used with my improved grate 100 incloses the bottom of said grate and is in-

clined downward and inwardly toward the bottom of an angle of from twenty to fifty degrees, and the front is curved to correspond with the form of the basket. This enables it 5 to receive the dust and ashes from the basket or grate and discharge it by gravitation into the ash-pit below.

The front B is fastened to the masonry by means of an iron turn-buckle, x, and hooked 10 rods y, threaded at one end with staples to receive the hook end, so that the frame can be held very firmly in place.

The sides and back of the fire-place are fitted 15 with movable plates held together by suitable joints or fittings, as shown at g, Fig. 3, and these may be taken out at any time to adjust the internal mechanism or to fit or take out the basket-bottom or make repairs.

The walls of the well or air-chamber in which 20 the grate is set are to be lined with asbestos or non-conducting fire-clay, or to be lined with non-conducting or heat-reflecting material, or bright metal, so as to prevent the absorption of useful heat by the walls surrounding the 25 air-chamber.

Having thus described my invention, what I claim as new, and desire to secure by Letters Patent, is—

1. A fire-place having the basket C and grate 30 D, a chamber, E, extending rearwardly from the grate-front and having passages through which air is admitted into the lower part and discharged from the upper part, in combination with a passage or flue, H, extending vertically within said air-space surrounded thereby, and having a transverse passage, G, passing through it and connecting the side air-spaces, as shown, a passage connecting said 35 smoke-flue with the upper part of the grate, a 40 damper, J, by which it is controlled, and a sec-

ond passage connecting the flue with the space below the grate with a damper, I, and an opening or ash-discharge, e, leading downward through the floor from this space, substantially as herein described.

2. A grate or fire-place having an air-chamber entirely surrounding the rear portion and sides, a supplemental vertical passage or smoke-flue, the upper end of which communicates with the chimney and also with the upper 50 part of the fire-place, and the lower end connects with the space beneath the grate and the ash-passage opening downwardly therefrom, in combination with dampers whereby the upper or lower connections with the grate may 55 be opened or closed, and a vertical transverse partition in the upper part of the smoke-flue, substantially as herein described.

3. A fire-place having its back and sides enclosed by an air-heating space, a supplemental 60 vertical flue, H, within said space surrounded by the hot air thereof and having a transverse passage or open partition, G, extending through it and connecting the side air-spaces, said flue having its upper end connected with 65 the chimney and also with the upper part of the fire-place, and the lower end connected with the space beneath the grate and the ash-discharge opening e, which leads downward therefrom, in combination with valves or dampers I J, whereby the draft may be directed 70 through either the upper or lower connecting passages from the grate and around the partition G, substantially as herein described.

In witness whereof I hereunto set my hand. 75

RICHARD SAVAGE.
